UNITED STATES PATENT OFFICE.

JOHN L. THORNTON, OF PROVIDENCE, RHODE ISLAND.

DESIGN FOR AN EMBLEMATIC BUTTON.

SPECIFICATION forming part of Design No. 36,611, dated November 3, 1903.

Application filed September 25, 1903. Serial No. 174,666. Term of patent 7 years.

To all whom it may concern:

Be it known that I, JOHN L. THORNTON, a citizen of the United States, residing at Providence, in the county of Providence and State of Rhode Island, have invented a new, original, and ornamental Design for Emblematic Buttons, reference being had to the accompanying drawings.

What I claim as new, and desire to secure by Letters Patent, is—

The ornamental design for an emblematic button, as shown.

In testimony whereof I have signed my name to this specification in the presence of two subscribing witnesses.

JOHN L. THORNTON.
